UNITED STATES PATENT OFFICE.

CHRISTOPHER BLINN, OF SPRINGBOROUGH, ASSIGNOR TO LOUIS C. ROYER,
OF DAYTON, OHIO.

GRAIN THRASHER AND SEPARATOR.

SPECIFICATION forming part of Letters Patent No. 259,264, dated June 6, 1882.

Application filed November 12, 1880. (No model.)

To all whom it may concern:

Be it known that I, CHRISTOPHER BLINN, of Springborough, in the county of Warren and State of Ohio, have invented certain new and useful Improvements in Grain Thrashers and Separators; and I do hereby declare the following to be a full, clear, and exact description of the same.

My invention relates to an improvement in 10 Grain Thrashers and Separators; and it is an improvement upon L. C. Royer's Patents of May 16, 1871, No. 114,974; of September 7, 1875, No. 167,570, and of June 20, 1876, No. 179,064. The present invention belongs to that class 15 of machines known as "oscillators" or "vibrators," in which the straw-conveying table has a reciprocating or vibrating motion; and the novelty consists in certain novel improvements, which will be fully understood from the following description, when taken in connection with the annexed drawings.

In the accompanying drawings, Figure 1 is a side elevation of my improved machine. Fig. 2 is a longitudinal vertical central section of 25 the same. Fig. 3 is a perspective of the deflector. Fig. 4 is a perspective view of the beater. Fig. 5 is a perspective view of the combined rake and beater.

The same letters of reference indicate the 30 same parts in all the figures.

The great desideratum in all thrashing-machines and separators is to arrest the straw, after it leaves the thrashing-cylinder, as speedily as possible and to deliver it over to 35 the grain-separating devices in order to prevent its being thrown through, or nearly through, the machine, and in order to effect perfect separation. This is the object of my invention, and I employ the following instrumentalities: The 40 frame-work of the machine is of the usual or any suitable construction, and contains the usual fanning and screening devices.

A represents the cylinder; B, the concave; C, the grate, and D the vibrating shaking-table, all of which parts may be constructed in 45 the manner represented, or in any other suitable way. Just in the rear of the cylinder A is a beater, E, revolving in the direction indicated by the arrow upon its pulley, and com-

posed of radial blades or wings a, extending 50 from a shaft, F, upon the end of which, on the outside of the machine, is a driving-pulley, G, Fig. 1. The blades or wings a, instead of being radial, may run past the center of the shaft F, if desired. This beater, as before stated, is 55 just in the rear of the thrashing-cylinder, and is as wide as the space between the sides of the machine. Its height above the shaker D is determined by the inclination of the grate or concave, and it should be so situated that 60 the straw leaving the thrashing-cylinder would be thrown directly against it, and not under it or above it.

In certain kinds or conditions of straw it 65 may be found useful to employ the curved deflector H, which should be set directly over the beater E.

Just behind the beater E is a combined revolving rake and beater, I, substantially such as shown in L. C. Royer's patents of September 7, 1875, and of June 20, 1876, before referred to, though the only essentials of this device are that, in addition to its having wings or blades to beat out the grain, it should have 70 also teeth to pull apart the bunches and aid in conveying the straw away from the beater E, and assist it in its passage through the machine. This rake and beater I is driven in the direction indicated by the arrow by a pulley, K, on the outside of the machine. The height 75 above the shaker D of both the beater E and rake I is immaterial, so long as they are not so high above it that the straw would be thrown under them by the thrashing-cylinder.

As before stated, the essential function of 80 the beater E is to catch the straw as it is thrown from the thrashing-cylinder and turn it down upon the shaker, by which the motion of the straw is arrested until the revolving rake catches it and pulls it away, thereby preventing the machine from choking up at this 85 point.

Having thus fully described my invention, I 90 claim—

1. In a thrashing and separating machine, 95 the combination of a revolving cylinder, a concave, a grate, a revolving beater arranged sufficiently near the cylinder to deflect the straw

downward, a revolving rake, and a vibrating shaker and carrier, all constructed and arranged to operate substantially as set forth.

2. In a thrashing and separating machine,
5 the combination of a thrashing-cylinder, a
grate, a rotary beater, a deflector, a rotary
beater which also acts as a rake, and a shaker,
substantially in the manner and for the pur-
poses described.
- 10 3. In a thrashing-machine and separator, the
combination of the following instrumentalities:
a thrashing-cylinder, a revolving beater di-

rectly in the rear of said cylinder, a deflector directly over said beater, a combined rake and beater directly in the rear of said deflector, 15 and a vibrating shaker under said beater, de-
flector, and rake, substantially as and for the
purpose specified.

In testimony whereof I have hereunto set
my hand.

CHRISTOPHER BLINN.
